UNITED STATES PATENT OFFICE

2,274,886

NASAL RESPIRATOR

Harold D. Carroll, Marion, Ohio

Application August 10, 1940, Serial No. 352,154

1 Claim. (Cl. 128—148)

My invention relates to improvements in nasal respirators for insertion in the nostrils to filter the air to prevent dust, pollen, and other impurities entrained in the air from passing into the nasal passages, and the primary object of the invention is to provide a simple and efficient arrangement of this character which is invisible when worn.

Other important objects and advantages of my invention will be apparent from a reading of the following description taken in connection with the drawing, wherein for purposes of illustration the preferred embodiment of my invention is shown.

In the drawing:

Figure 1 is a general schematic view showing one of my respirators mounted in the nostril.

Figure 2 is a view looking toward the small end of the respirator and as shown by the arrow in Figure 1.

Figure 3 is a bottom plan view, and looking in the direction of the arrow shown in Figure 1.

Figure 4 is an enlarged longitudinal vertical sectional view, the section being taken on line 4—4 of Figure 3.

Figure 5 is a plan view of the spring retaining ring.

Referring in detail to the drawing, the numeral 5 generally designates the respirator which is preferably formed of a single piece of suitable material, such as plastic, providing the flat horizontal floor 6 whose longitudinal edge 7 is substantially straight and whose opposite longitudinal edge 8 is longitudinally bowed. The heel end of the floor 6 is symmetrically rounded as indicated by the numeral 9 while the opposite end is asymmetrically rounded as indicated by the numeral 10, so that the heel area of the bottom is slightly smaller in area than the toe region. The toe region is provided with a plurality of relatively closely spaced holes 11 to admit air into the interior of the respirator body, while the intermediate part of the floor 6 and the heel area thereof are provided with respective openings 12 and 13 separated by a transverse bar 14. The opening 12 is substantially square in shape while the opening 13 is substantially semi-circular in shape.

A continuous wall rises from the edges of the bottom or floor 6, the said wall being composed of the relatively short rearwardly inclining front wall portion 15 following the contour of the toe region of the floor 6, the relatively high or tall wall portion 16 which extends substantially perpendicularly and then is rearwardly and up-

wardly curved as indicated by the numeral 17 in Figure 4, the shape of this wall conforming to the shape of the heel region of the floor 6. An inner wall portion 18 arises from the straight longitudinal edge 7 of the floor 6 while another longitudinal wall portion 19 rises from the curved or bowed edge 8 of the floor 6, the wall portions 18 and 19 being connected with and merged into the end wall portions 15 and 16, with the upper edges 10 of the side wall portions inclining upwardly and rearwardly in a graduated manner as indicated in Figure 4. In addition the wall portion 18 is inwardly curvedly deflected as indicated in Figure 2, while the wall portion 19 is outwardly curvedly deflected as also indicated in Figure 2. The upper edges of the various wall portions cooperate to produce the oval aperture 20 which has rounded and smoothed edges.

A replaceable pad of lamb's wool or the like 20 designated by the numeral 21 lies removably on the top of the floor 6 and over the holes 11 and the openings 12 and 13, and this is held removably in place by a spring wire loop 22 which when placed on top of the pad within the side walls of 23 the respirator springs open to conform to the contour of the walls and clamp the pad down in place. The spring loop and the pad may be easily removed for replacement by a simple tool. The pad 21 will be soaked with medicinal mineral oil of suitable character to increase the filtering effect of the pad and to provide the desired medication.

As indicated in Figure 1 of the drawing, the curved rear wall 16 is placed against the rear 35 wall of the nostril as indicated by the numeral 23, when the respirator is inserted in the nostril so that the slanting front wall 15 bears as indicated by the numeral 24 on the front part of the nostril, while the side wall 18 bears against the 40 cartilage between the nostril and the outer wall 19 bears against the side of the interior of the nostril, all at a level above the lower end of the nostril so as to be out of sight when worn.

Although I have shown and described herein a 45 preferred embodiment of the invention, it is to be definitely understood that I do not wish to limit the application of the invention thereto except as may be required by the scope of the subjoined claim.

50 What is claimed is:

A nasal respirator comprising a body consisting of a bottom plate, said plate having large openings in its rear portion and perforations in its front portion, a wall rising from the edges of 55 said bottom plate, a medicated air filtering ele-

ment resting upon said bottom plate over the perforations thereof, and removable means holding said pad down in place, said body being horizontally elongated and formed with rounded ends, the inner longitudinal side of said body being substantially straight and the outer longitudinal side of said body being laterally outwardly curved, the front end wall being short and sloping upwardly and inwardly to fit in the front portion of a nostril, the rear wall being much

longer than the front wall and having its lower part substantially straight and the rest of the rear wall curving upwardly and rearwardly to fit in the lower sinus, the side walls having their upper edges sloping downwardly and forwardly from the top of the rear wall to the top of the front wall and the two end walls and the side walls merging to provide a substantially oval orifice.
